DESIGN FOR AN ANALYTICAL ROTOR FOR ULTRA-CENTRIFUGE MACHINES

Joseph Grebmeier, Menlo Park, Calif.

Application July 18, 1946, Serial No. 131,681

Term of patent 14 years

(Cl. D55—1)

To all whom it may concern:

Be it known that I, Joseph Grebmeier, a citizen of the United States, residing at Menlo Park, county of San Mateo, State of California, have invented a new, original, and ornamental Design for an Analytical Rotor for Ultra-Centrifuge Machine, of which the following is a specification, reference being had to the accompanying drawing, forming a part thereof.

In the drawing:

Figure 1 is a side view of the analytical rotor for ultra-centrifuge machines showing my new and ornamental design;

Fig. 2 is a top plan view of the analytical rotor for ultra-centrifuge machines of Fig. 1; and

Fig. 3 is a vertical sectional view taken on line 3—3 of Fig. 1.

I claim:

The ornamental design for an analytical rotor for ultra-centrifuge machines, substantially as shown.

JOSEPH GREBMEIER.
